UNITED STATES PATENT OFFICE.

ALEXANDER ADAMSON, OF AKRON, OHIO.

COLLAPSIBLE CORE.

1,177,756.

Specification of Letters Patent.

Patented Apr. 4, 1916.

Application filed January 7, 1915, Serial No. 975. Renewed February 21, 1916. Serial No. 79,798.

To all whom it may concern:

Be it known that I, ALEXANDER ADAMSON, a citizen of the United States, residing at Akron, in the county of Summit and State 5 of Ohio, have invented new and useful Improvements in Collapsible Cores, of which the following is a specification.

This invention relates to improvements in collapsible cores for the manufacture of 10 tire shoes or casings of double tube pneumatic tires, and the primary object of the invention resides in the means employed for holding and locking the sections of the core body in assembled relation, said means being effectual for the purpose, easily operated to 15 insure perfect alinement of the core sections when assembled, and providing means for the ready collapsing of the core.

With the foregoing and other objects in 20 view, the invention consists in the novel construction, combination and arrangement of parts constituting the invention to be herein-after specifically described and illustrated in the accompanying drawings which form 25 a part hereof wherein is shown the preferred embodiment of the invention, but it is to be understood that changes, variations and modifications can be resorted to which come 30 within the scope of the matter hereinafter claimed.

In the drawings in which similar reference numerals indicate like parts in the different figures, Figure 1, is a plan view of a core assembled embodying this invention; 35 Fig. 2, is a side elevation of a ring employed in assembling a core; Fig. 3, is a view partly in section and partly in perspective of one of the interlocking members attached to one section of the core; Fig. 4, is a view similar 40 to Fig. 3 of the complementary interlocking member of the core; and, Fig. 5, is a transverse sectional view of a core on line X, X of Fig. 1.

A ring core embodying this invention is 45 customarily constructed of a plurality of segment-shaped sections which when united together as hereinafter described constitute an annulus, the outer and lateral faces of which are shaped to impart a preferred configuration to the corresponding inner face of the tire or tire shoe which is to be manufactured thereon. The sections which are employed to form the annular core are designated in the drawing by the reference numerals 1, 2, 3 and 4 and are provided with

inwardly extending flanges 5. These flanges are all similar and may be, if desired, provided on their inner lateral faces with laterally-projecting ribs 6. The junction lines 7 between the ends of the section 1 and the sections 2 and 3 are so inclined that the member 1 is substantially wedge-shaped to constitute a key-forming member. The joints between the sections 2, 3 and 4 are approximately radial with respect to the assembled core. The means for interlocking the ends of contiguous sections together are all identical and hence, a description of one is believed to be sufficient for the understanding of the invention and the description will be confined to the interlocking of one end of section 1 with the contiguous end of the section 2. The end of the section 2 is provided with a recess 8 extending centrally of the core body from the inner face of the flange 5 and terminating near the outer face or perimeter of the core body. Mounted in this recess is a member 9 the main portion of which is narrower than the depth of the recess 8 and is secured thereon by means of hold-fast devices 10. The outer end of the member 9 is provided with a head 11 the lateral face of which is approximately flush with the end of the core section, and between the head 11 and the body portion 9 of this member is an inclined shoulder 12 which extends transversely of the member 9.

The contiguous end of the section 1 is provided with a centrally-positioned recess 13 which extends from the inner face of the flange 6 outwardly and from which extends and at right angles thereto a second recess or pocket 14. Adapted to be positioned in the recesses 13 and 14 is a T-shaped member 15 of a greater width than the depth of the recess so as to project therefrom and which is secured in position through the means of hold-fast devices 16. The outer end of the member 15 is provided with an inclined face 17 for a purpose to be later described. The member 15 is provided with an extension or stem 18 preferably cylindrical, or if not cylindrical, corresponding in contour to the configuration of the recess 14 and this stem is adapted to be positioned therein. The stem 18 is provided with a conical recess 19 near its end. Extending outwardly and centrally from the inner face of the flange 6 to the recess 14 is a threaded opening in which is positioned a set screw 20 of considerably 110

less diameter than the transverse diameter of the recess 19 and provided with a conical working point adapted to engage in the conical recess 19.

5 In practice, it is preferable to place a plurality of filler strips 21 in the bottom of the recess 13 for a purpose to be later described.

The sections are adapted to be held in position when assembled through means of a 10 ring 22 having at least one slightly rounded or beveled corner 23 and further provided with a V-shaped inner groove 24 for a purpose to be later described.

In assembling a core constructed in accordance with this invention, the sections of 15 the core which are provided at their ends with the members 15 are moved radially outwardly so that the inclined ends 17 of these members will interlock with the inclined shoulders 12 of the members 9 and prevent further outward movement of these members, thus setting up interengaging union between contiguous ends of the core sections. After assembling of the core and 20 interlocking of the ends as just described, the ring 22 is forced into position against the inner faces of the flanges 6 which serves to wedge the members outwardly as far as they are capable of going, and thereby perfectly alining the members of the core circumferentially and at the same time the members 15 serve to prevent any lateral distortion of the core sections. The groove 24 in the inner face of the ring 22 is provided 25 to enable the pointed ends of the chuck to engage therein during the building up of a tire. In cases where the outer inclined ends of the member 15 and the shoulders 12 become worn so that in use the sections which 30 are provided with the members 15 are inclined to get out of alinement due to the wear on the interlocking members one or more of the lining strips 21 are removed and the member 15 shifted farther into the recess 13. This shifting may be accomplished 35 by manipulating the set screw 20 which engages only one wall of the recess 19 and acts as a wedge for shifting the position of the member 15. At the same time the hold-fast devices 16 may be used for securely holding 40 the member 15 in position.

I claim:—

1. A collapsible core for the manufacture 45 of tire shoes or casings comprising a series of segment shaped sections adapted to be assembled into a circular core with their ends abutting against each other and each section formed with an inwardly-inclined flange, said sections provided with 50 interengaging means at the ends thereof, said interengaging means embodying a hook-shaped lug at one end of one section, and a lug provided with a portion fashioned to engage said hook-shaped lug on the contiguous end of a coadjacent section, and a 55

ring positioned within said core and adapted to bear outwardly against the inner faces of the flanges to force the sections outwardly and into circumferential registration.

2. A collapsible core for the manufacture 70 of tire-shoes or casings comprising a series of segment-shaped sections adapted to be assembled into a circular core with their ends abutting against each other and each section formed with an inwardly-inclined flange, said sections provided with interengaging means at the ends thereof, said interengaging means embodying a hook-shaped adjustable lug at one end of one section, and an adjustable lug provided with a portion 75 fashioned to engage said hook-shaped lug on the contiguous end of a coadjacent section, and a ring positioned within said core and adapted to bear outwardly against the inner faces of the flanges to force the sections outwardly into circumferential registration. 80

3. A collapsible core for the manufacture 90 of tire-shoes or casings comprising a series of segment shaped sections adapted to be assembled into a circular core with their ends abutting against each other and each section formed with an inwardly-extending flange, said sections provided with interengaging means at their ends, said interengaging means embodying a hook-shaped lug having an inclined portion at one end of one section, and a lug on the contiguous end of a coadjacent section, and provided with an inclined portion adapted to interengage with 95 the lug on the first section, and a ring positioned within said core and adapted to bear against the inner faces of the flanges to force the sections outwardly into complete circumferential registration. 100

4. A collapsible core for the manufacture 110 of tire-shoes or casings comprising a series of segment shaped sections adapted to be assembled into a circular core with their ends abutting against each other and each section formed with an inwardly-extending flange, said sections provided with interengaging means at their ends, said interengaging means embodying a hook-shaped lug on one section and a complementary lug on a 115 coadjacent section, said lugs adapted to interengage, a stem on one of said lugs projecting into the core body, an outwardly-movable member engaging said stem for shifting and locking said stem and lug in 120 position, and a ring positioned within said core and adapted to bear against the inner faces of the lugs to force the sections outwardly and into circumferential registration. 125

5. A collapsible core for the manufacture 130 of tire-shoes or casings comprising a series of segment-shaped sections adapted to be assembled into a circular core with their ends abutting against each other and each

section formed with an inwardly-extending flange, said sections provided with interengaging means at the ends thereof, said interengaging means embodying a pair of lugs each of which is mounted on the opposing end of a section, said lugs fashioned to interlock, and a ring positioned within said core and adapted to bear against the inner faces of the flanges to force the sections out-

wardly and into complete circumferential 10 registration.

In testimony whereof I have hereunto set my hand in presence of two subscribing witnesses.

ALEXANDER ADAMSON.
